US0D1036819S

(12) **United States Design Patent** (10) Patent No.: **US D1,036,819 S**
(45) Date of Patent: ** Jul. 30, 2024

(54) **GLITTER SNEAKER**

(71) Applicant: **Jiongbin Lin**, Zhangzhou (CN)

(72) Inventor: **Jiongbin Lin**, Zhangzhou (CN)

(**) Term: **15 Years**

(21) Appl. No.: **29/934,398**

(22) Filed: **Mar. 26, 2024**

(51) LOC (14) Cl. 02-04

(52) U.S. Cl.

USPC **D2/902**
